(57) **CLAIM**

The ornamental design for a snowshoe, as shown and described.

DESCRIPTION

1. Snowshoe

1.1 : Top

1.2 : Exploded

1.3 : Front

Snowshoe adapted for mounting on a shoe equipped with an ice spike device comprising a plate in the form of a horse-shoe which can block the relative displacements of the plate with respect to the shoe.

1 Claim, 3 Drawing Sheets

FIG.1.1

FIG.1.2

FIG.1.3
